FIRE HOSE NOZZLE

William H. Lauderback, Longview, Tex., and William S. Thompson, Elkhart, Ind., assignors, by direct and mesne assignments, to Elkhart Brass Manufacturing Company, Elkhart, Ind., a corporation of Indiana

Application November 17, 1958, Serial No. 774,386

3 Claims. (Cl. 239—439)

This invention relates to fire hose nozzles and, like 15 the pending application of William H. Lauderback, Serial No. 643,155, filed February 28, 1957, and now abandoned, of which this is a continuation-in-part, refers more particularly to fire hose nozzles which may be adjusted to project either a straight solid stream of water or a cone of fog.

In fighting fires with water, certain conditions and types of fires require that the water be applied in a solid, far reaching stream. Other fires are best extinguished by applying the water in the form of a saturated fog. Since the conditions encountered in the fighting of fires are apt to change rapidly, it is highly desirable that the nozzle used to apply the water be readily and quickly adjustable to deliver either a straight stream or a cone of fog.

Such dual purpose nozzles have been in use for some time and have proved very effective, but many fires cannot be extinguished by water alone. For such fires, a foam of one kind or another must be used. The foam may be produced either chemically or mechanically, but heretofore when foam had to be used, a special single purpose nozzle was required.

The disadvantage of having to use special equipment or nozzles for applying foam should be obvious, but to illustrate the point, it is not uncommon for a fireman engaged in "chasing" a fire with a fog nozzle to suddenly come upon a fire source which can only be handled with foam. When this happened in the past, the fireman had to retreat and come back with a foam nozzle fed either from the foam truck or a portable pressure tank.

Recognizing this disadvantage, the present invention has as its purpose to provide an adjustable fire hose nozzle, which not only is capable of projecting a solid stream of water and a cone of fog, but also can be used to lay down a blanket of foam.

Thus, with the nozzle of this invention, any condition that might be encountered can be met immediately by the nozzle man, for when he finds the need for using foam, all he has to do is request the engine or truckman to open the foam valve on the truck. This injects a foaming agent into the stream being fed to the nozzle; but, of course, the nozzle must be capable of mechanically converting the resulting solution into foam.

The nozzle of this invention is not only capable of mechanically producing foam, but is very effective in this respect. In fact, its ability to produce and lay down a blanket of foam might be considered phenomenal. In one specific test of the nozzle to determine its effectiveness to generate foam, the foam produced was discharged into an area enclosed by a four foot high

2

earthen dike surrounding a group of oil storage tanks. The dike was rectangular, 80 feet long and 40 feet wide. A standard foaming agent was introduced into the stream (of course, before it issued from the nozzle) at 5 the rate of fifty gallons per minute.

In forty seconds the entire diked area was filled to overflowing.

Also, it has been found that the nozzle of this invention produces better results even when used to project a 10 solid straight stream of water or a cone of fog. The reach of the solid stream has been increased by almost twenty percent, and the cone of fog is not hollow as it was so often in the past, but of uniform density throughout.

In general, the conventional adjustable fog nozzle—which preceded this invention—comprises telescoped front and rear sections, having a screw threaded connection therebetween to enable the front section to be adjusted back and forth with respect to a disc-like pattern 20 determining head fixed to the rear section and located in the mouth of the front section. This head coats with the wall and edge of the nozzle mouth to determine the shape and pattern of the discharge.

When the front nozzle section is in its forward position of adjustment the disc-like head is well within and to the rear of the mouth of the nozzle so that the water issues in a solid straight stream, but as the nozzle is adjusted to move its front section rearward, the pattern determining head is brought progressively farther forward in the mouth of the nozzle and finally lies well in front of the mouth. By this adjustment the pattern of the discharging water changes from a straight stream to a diverging conical spray, the angle of which increases as the front nozzle section is adjusted rearward.

35 Circumferentially spaced forwardly projecting teeth on the edge or lip of the nozzle mouth break up the conical spray into a fine mist or fog and to a degree deflect some of the water into the hollow of the formed cone, but do not affect the straight stream.

40 This past structure proved to be a fairly satisfactory combination straight stream and fog nozzle, but it was not suitable with foam. To illustrate its deficiency in this respect, one of these prior nozzles was compared with the nozzle of this invention during the test hereinbefore described. Whereas the nozzle of this invention filled the entire diked area to overflowing in forty seconds, the prior nozzle produced foam so poorly that at the end of a full minute of operation the depth or thickness of the blanket of foam in the diked area was only 45 six inches. Of course, all conditions were the same for both nozzles—the nozzles were of the same size, the same standard foaming agent was introduced into both streams at the same rate, and the pressure was the same. In addition, the conical spray delivered by the nozzle 50 when adjusted to its "fog" position, was substantially hollow, and the distance that could be reached by the solid straight stream was only about 80% of that reached with the nozzle of this invention.

While at first it was not known just why and how 55 the fire hose nozzle of this invention was so effective to produce or generate foam, it now seems clear that two conditions must be present to achieve the desired results. A low pressure zone must be created within the hollow stream defined by the "wall" of foam producing solution issuing from the nozzle; and violent

turbulence must exist inside the hollow stream directly ahead of the nozzle. The creation of a low pressure zone inside the hollow stream causes a positive inspiration of air through the "wall" of the foam producing solution, and the turbulence at the inside of the stream effects the needed rapid aeration of the solution. The larger the volume of the air drawn into the stream and the more violent the turbulence, the better will be the production of foam.

Upon this assumption, it is an object of this invention to provide a fire hose nozzle of the character described having its pattern determining head provided with a multiplicity of uninterrupted passages extending therethrough and so arranged that the jets issuing therefrom impinge one another at the center of the stream a few inches ahead of the nozzle.

Still another and more specific object of this invention is to have the passages through the pattern-determining head formed by holes which are shaped to effect an accelerating high velocity flow therethrough to thus achieve maximum pressure reduction and most effective turbulence at the center of the stream.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate two complete examples of the physical embodiments of the invention constructed according to the best modes so far devised for the practical application of the principles thereof, and in which:

Figure 1 is a longitudinal sectional view through a fire hose nozzle embodying this invention in its preferred form;

Figure 2 is an enlarged fragmentary sectional view through the front end of the nozzle to illustrate particularly the manner in which the jets issuing from the holes in the pattern-determining head function when the nozzle is being used to generate foam;

Figure 3 is a detail cross sectional view through Figure 2 on the plane of the line 3-3;

Figure 4 is a view partly in side elevation and partly in longitudinal section illustrating that embodiment of the invention disclosed in the aforesaid Lauderback application, of which this is a continuation-in-part; and

Figure 5 is a front end view of the nozzle shown in Figure 4.

Referring to the drawings, and particularly to sheet one thereof, it will be seen that the nozzle of this invention comprises a rear or inlet section 7 which is connectible to a hose 8, and a front outlet section 9 which is telescoped over the fore part of the rear section. Together these sections provide a flow passage 5 of substantially uniform open area from the inlet to the outlet of the nozzle. A screw threaded connection 10 joins the two sections and provides means operable by relative rotation of the sections to adjust the front section axially back and forth with respect to the rear section. By such adjustment, which is facilitated by a rubber collar or grip 9' on the front section, the position of a pattern-determining head 12 in the mouth 13 of the nozzle is set to produce either a solid straight stream or a diverging conical stream. With the front nozzle section in its foremost position of adjustment, the head 12 is well within and to the rear of the nozzle mouth so that the peripheral surface of the head and the cylindrical wall of the bore defining the mouth 13 coact to produce an annular discharge opening having axially straight concentric sides. This adjustment produces the straight solid stream.

As the nozzle is adjusted to draw its front section

5

rearward so that the head 12 moves forward in the mouth 13, the pattern of the discharging water changes from a straight stream to a diverging cone, the angle of which increases as the front section approaches its rearmost position shown in Figure 1. At this point, the head 12 is entirely out of the mouth 13 so that the water striking the upstream side of the head and deflected thereby radially outward is not redirected forward, and as a result the angle of the discharging cone is at its maximum which is about 145°.

10

It is to be noted that the edge or lip of the nozzle mouth is defined by a widely outwardly flaring conical surface 14, the angle of which determines the maximum divergence of the conical discharge. A row of circumferentially spaced teeth 15 project forwardly from the wall 14 to break up the discharging conical stream into a fine mist or fog. To a degree these teeth also deflect some of the water inwardly, but when the nozzle is adjusted to deliver a straight stream, the teeth have no function.

15

As noted hereinbefore, the pattern-determining head is fixed coaxially to the fore part of the rear nozzle section. For this purpose, a spider-like support 16 is formed in the front end of the rear nozzle section, with the hub 17 thereof coaxial with the nozzle and receiving the rear end of a stem 18 projecting rearwardly from the head. Since the hub 17 and the arms 19 of the spider-like support occupy part of the cross sectional area of the flow passage, and since it is desirable to have the open cross sectional area of the flow passage vary as little as possible along the length thereof, the diameter of the flow passage adjacent to the support 16 is increased as at 5'.

20

Flow through the nozzle may be controlled by a shut-off valve indicated generally by the numeral 20. This valve comprises a ball element 21 mounted in the rear nozzle section for rotation about an axis transverse to that of the nozzle and provided with a hole 22 diametrically therethrough. The hole 22 is preferably of the same size as the nominal diameter of the flow passage; and a handle 23 connected with the ball element provides means for rotating the ball from its full open position shown in Figure 1, to a shut-off position at right angles thereto.

25

It should be understood, however, that while it may be desirable to provide the nozzle with a shut-off valve, the invention is by no means limited to nozzles so equipped.

30

To the extent thus far specifically described, the structure is substantially the same as it has been in combination straight flow and fog nozzles heretofore available. Such nozzles, as has been brought out hereinbefore, were not suitable for use with foam. However, a relatively simple structural change admirably adapts these nozzles for use in laying down foam. By the simple expedient of providing a multiplicity of passages 25 through the pattern-determining head 12, and having these passages shaped and arranged in a particular way, the nozzle not only is adjustable to project a straight stream of water and a cone of fog, but in addition is tremendously effective for the mechanical production of foam.

35

In the preferred embodiment of the invention shown in Figures 1, 2 and 3, inclusive, the passages 25 are provided by drilled holes arranged in two concentric circles with the axes of all of the holes converging upon a single point on the nozzle axis a short distance in front of the nozzle. Accordingly, the streams or jets of water which issue from these holes impinge one another and break up into a fine mist or fog which completely fills the interior of the space defined by the "wall" of water issuing from the annular opening between the periphery of the head 12 and the edge of the mouth 13. Thus, when the nozzle is adjusted to any of its "fog" positions the cone of fog discharged by the nozzle has substantially

uniform density throughout, as distinguished from the more or less hollow cones delivered by the prior nozzles in which the pattern-determining head was imperforate. The presence of the holes 25 through the head 12 even improves the performance of the nozzle when adjusted to deliver a solid straight stream. At least a twenty percent increase in the reach of the straight stream has been observed.

Most important, however, the presence of the holes 25 enables the nozzle to be used with foam.

The streams or jets issuing from the holes 25 tend to evacuate the interior of the hollow stream issuing from the mouth of the nozzle, and thus, as indicated in Figure 2, create a low pressure zone inside the hollow stream. By virtue of this low pressure zone, air is drawn through the "wall" of water forming the hollow stream to commingle with and aerate the stream and the jets issuing from the holes as they impinge and break up.

When the nozzle is being used to lay down foam, it is of course understood that a suitable foaming agent is introduced into the stream flowing to the nozzle. This forms a solution which upon agitation in the presence of air, whips up into a foam. By virtue of the large volume of air drawn into the discharging stream in the manner described and the impingement of the jets upon one another in the highly aerated center of the cone, the solution of water and foaming agent is rapidly converted into foam.

Maximum effectiveness for foam generation is obtained when the holes 25 are larger at their upstream or inlet ends than they are at their downstream or discharge ends. With the holes so shaped two important advantages are realized, (1) full volume flow through the holes is assured, and (2) the velocity of the flow through the holes is accelerated so that the discharging jets travel at higher velocity. This increases the amount of air drawn into the center of the stream and renders the turbulence caused by the impinging jets more violent.

By test it was found that the most effective adjustment of the nozzle for the generation of foam is somewhere between the straight stream and 30° fog positions. This is approximately the position shown in Figure 2.

Although the holes 25 could be tapered for their entire length, satisfactory results are obtained if their upstream ends are countersunk as at 26. To facilitate drilling and countersinking the holes, the upstream face of the head has a central conical portion 27 in line with and substantially normal to the axes of these holes, and a conical bottomed groove 28 near its periphery in line with the outer circle of holes.

It is significantly important that the passage 25 provided by the holes extend uninterruptedly from the upstream side or face of the pattern-determining head to the downstream side thereof, and that the upstream side or face of the head be exposed directly to and crosswise of the flow passage.

Also, so as not to detract from or interfere with the formation of a wide angle cone of fog, the area of the annular space or outlet between the periphery of the pattern-determining head and the wall of the bore forming the nozzle outlet 13 should be larger than the combined area of the passages 25. The ratio between these areas is not critical and will vary with the different nozzle sizes, but in no case should it be much less than one to two. This minimum ratio would obtain in the smaller size nozzles; for larger nozzles the ratio may be as high as one to ten.

As noted, Figures 1, 2 and 3 illustrate the invention adapted to a fire hose nozzle of relatively small size. Figures 4 and 5, on the other hand, show the invention applied to a larger size nozzle. In this nozzle there is no shut-off valve such as that employed in the preferred embodiment, and the cylindrical mouth 30 of the front section is considerably larger in diameter in proportion to

its axial length, the flow passage being abruptly enlarged, as at 31, in its approach to the mouth 30.

As in the other embodiment of the invention, the mouth 30 also opens to a widely outwardly flaring conical surface 32 which has a row of circumferentially spaced forwardly projecting teeth 33 thereon for the same purpose as hereinbefore described. The pattern-determining head 34 in this form of the invention, is also mounted by means of a stem 35 extending rearwardly therefrom and secured in the hub 36 of a spider-like support 37 fixed in the rear nozzle section. To accommodate the arms and hub of the support 37 without decreasing the open cross sectional area of the flow passage, the latter is enlarged at its medial portion where the support is located.

As in the smaller nozzle, relative rotation between the inner and outer nozzle sections adjusts the pattern of the stream issuing from the nozzle. In this embodiment of the invention, however, the holes 38 which define the passages through the pattern-determining head, are of uniform size from end to end, and although they are arranged in concentric circles as before and have their axes converging inwardly, they do not all converge upon a single point, but upon several points spaced along the axis of the nozzle. The important thing is that the jets issuing from the holes impinge upon one another, and for this it is only necessary that the holes be so arranged that each will pair with another to deliver jets that impinge forwardly of the nozzle, on the nozzle axis or elsewhere within the hollow stream.

While tests have shown that the accelerated flow through the holes in the pattern-determining head obtained when these holes are nozzle-shaped, i.e. reduced in size from inlet to outlet, and having their axes converging upon a single point yields the best results, particularly in the formation of foam, the construction shown in Figures 4 and 5 possess great advantages over prior nozzles.

From the foregoing description taken in connection with the accompanying drawings, it will no doubt be apparent to those skilled in the art, that this invention makes it possible for the first time to use a combination straight stream and fog nozzle in the generation and laying down of foam, and that, in addition, it improves the performance of such dual purpose nozzles when used to project a straight solid stream of water or a cone of fog.

What is claimed as our invention is:

1. In a fire hose nozzle, the combination of: means defining a tubular nozzle body having an inlet at its rear, an outlet at its front, and a flow passage extending from the inlet to the outlet, the front end of the body being widely flared so that the mouth of the outlet is substantially larger in diameter than the portion of the flow passage directly therebehind; a stem carried by the nozzle body and extending coaxially forwardly therein toward its outlet; and an enlarged substantially flat disc-like head on the front of said stem and in the mouth of the nozzle, said head having a closed central portion ahead of the stem and having a substantially flat rear surface which is substantially normal to the nozzle axis and which is exposed directly to the pressure of liquid in that portion of the flow passage immediately behind the head, the diameter of the head being larger than the portion of the flow passage directly therebehind and coaxing with the mouth of the outlet to define an annular discharge for the nozzle through which liquid delivered under pressure at the nozzle inlet may discharge in the form of a hollow stream, said head having a number of small holes extending uninterruptedly forwardly therethrough from its substantially flat rear surface so that liquid will be forced directly from said flow passage through said holes in the form of fast moving jets to thereby create a low pressure zone in front of the head and within the hollow stream, into which air is drawn, said holes being arranged on a

plurality of spaced circles which are concentric to the nozzle axis with the holes on the outer circle located near the periphery of the head and having their axes converging forwardly, and said holes being arranged in pairs to produce jets of liquid that violently impinge one another at points which lie within the forward projection of the periphery of the head, so that the jets will break up into a mist which is dispersed in air drawn into said zone and will move forwardly along with the hollow stream issuing from the annular discharge around the head without interfering with said hollow stream.

2. The fire hose nozzle of claim 1, wherein the holes

10

on adjacent circles are arranged in pairs, the axes of which converge forwardly toward the nozzle axis.

3. The fire hose nozzle of claim 1, further characterized by the fact that said holes are enlarged at the rear of the head to facilitate the entry of liquid thereinto and to assure that the jets issuing from the holes will travel at high velocity.
